TELEVISION SYNCHRONIZING AND
CONTROL SYSTEMHarold M. Lewis, Great Neck, N. Y., assignor to
Hazeltine Corporation, a corporation of Delaware

Application October 5, 1938, Serial No. 233,371

10 Claims.

(Cl. 178—7.5)

This invention relates to television receiving apparatus and more particularly to synchronizing and control systems for such apparatus. The invention is especially directed to the provision of a combined synchronizing-signal-separating and automatic amplification control system for television receivers.

In accordance with present television practice, a transmitted signal comprises a carrier wave modulated by light-modulation components representative of varying light values in successive incremental areas of an image being transmitted and of its average background illumination, and synchronizing-modulation components which correspond to initiations of successive lines and fields in the scanning of the image. The latter components ordinarily have amplitude values outside of the amplitude range of the light-modulation components and extending in the direction of black.

At the receiver, a beam is so deflected as to scan and illuminate a target in a series of fields of parallel lines. The synchronizing-modulation components of the received signal are utilized to control the scanning apparatus so as to synchronize its operation with that of similar apparatus utilized at the transmitter in developing the signal. The intensity of the cathode ray is controlled by the video-frequency components of the received signal, as well as by the unidirectional background illumination voltage developed in the receiver, thereby to reconstruct the transmitted image.

Essential functions which must be performed in a television receiving system of the type described include deriving from the signal separate line-frequency and field frequency synchronizing pulses as well as developing a unidirectional-bias voltage representative of the average intensity of the carrier and independent of its light modulation and the utilization of this voltage automatically to control one or more operating characteristics of the receiver, for example, to effect automatic amplification control. Various methods have heretofore been devised for performing these functions but, in general, they have involved relatively complicated and/or unstable apparatus, or have otherwise left something to be desired.

It is an object of the present invention to provide, in a television signal-reproducing system wherein the received signal includes combined light-modulation components and synchronizing-modulation components having amplitude values outside the amplitude range of the light-modulation components, combined means for deriving

from the received signal the synchronizing components separate from the other modulation components and a unidirectional control-bias voltage representative of the average intensity of the received signal and independent of the light-modulation components.

In accordance with the present invention, there is provided a television receiver adapted for reproducing a signal carrier having combined light-modulation components and synchronizing-modulation components, the latter having amplitude values outside the amplitude range of the light-modulation components. The receiver includes a rectifying device, means for deriving from a signal translated by said receiver a signal having components representing the peaks of said synchronizing modulation components at a level corresponding to the unmodulated peaks of said carrier wave, and means for applying the derived signal to the rectifying device which includes means for maintaining the peaks of the synchronizing signals at the above-mentioned level to derive the synchronizing components separate from the other modulation components and a control effect, such as a unidirectional bias voltage, proportional to the average intensity of the received signal carrier and independent of its light-modulation components. Means are further provided for utilizing the derived synchronizing components for synchronizing the operation of the receiver and for utilizing the control effect for controlling an operating characteristic of the receiver, for example, for automatic amplification control. A preferred embodiment of the invention includes a diode rectifier for developing the bias voltage and impedance means connected in circuit with the same diode rectifier for deriving the synchronizing components.

For a better understanding of the invention, together with other and further objects thereof, reference is had to the following description taken in connection with the accompanying drawing and its scope will be pointed out in the appended claims.

45 In the accompanying drawing, Fig. 1 is a circuit diagram, partially schematic, of a cathode-ray tube television reproducing system including circuits embodying the present invention; Fig. 2 is a group of curves representing certain operating characteristics of the system of Fig. 1 to aid in the understanding of the invention; and Fig. 3 is a circuit diagram illustrating a modified form of the invention.

Referring now more particularly to the drawing, the system there illustrated comprises a re-

ceiver of the superheterodyne type including an antenna system 10-11 connected to a radio-frequency amplifier 12, to which is connected, in cascade in the order named, an oscillator-modulator 13, an intermediate-frequency amplifier 14, a detector 15, a video-frequency amplifier 16 and an image-reproducing device 17 which may be a cathode-ray signal-reproducing tube, these stages or units constituting the main signal-translating channel of the receiver. A line-frequency generator 18 and a field-frequency generator 19 are also coupled to the output circuit of the amplifier 14, by way of synchronizing-signal-separating apparatus presently to be described, and to the scanning elements of the image-reproducing device 17 in the conventional manner. The stages or units 10-19 may all be of conventional well-known construction so that detailed illustrations and descriptions thereof are deemed unnecessary herein.

Referring briefly, however, to the operation of the system described above, television signals intercepted by the antenna circuit 10-11 are selected and amplified in the radio-frequency amplifier 12 and supplied to the oscillator-modulator 13, where they are converted to intermediate-frequency signals which, in turn, are selectively amplified in the intermediate-frequency amplifier 14 and delivered to the detector 15. The modulation components of the signal are derived by the detector 15 and are supplied to the video-frequency amplifier 16 wherein they are amplified and from which they are supplied in the usual manner to a brilliancy-control element of the image-reproducing device 17.

The intensity of the scanning beam of the device 17 is thus modulated or controlled in accordance with the light-modulation voltages impressed upon the control element of the device 17 in the usual manner. Saw-tooth voltage or current waves generated in the line-frequency and field-frequency generators 18 and 19, respectively, which are controlled by synchronizing-voltage pulses supplied from the apparatus of this invention as presently to be explained, are applied to the scanning elements of the device 17 to produce electric scanning fields, thereby to deflect the ray in directions normal to each other so as to trace a rectilinear scanning pattern on the screen of the tube and thereby to reconstruct the transmitted image.

Referring now more particularly to the portion of the system of Fig. 1 embodying the present invention, for the purpose of developing a control-bias voltage, there is provided a control signal-translating channel, separate from the main signal-translating channel previously described, and comprising a vacuum-tube amplifier 20 and a rectifier device 21 connected in the order mentioned. The tube 20 may be of any suitable type having an input circuit comprising a coupling condenser 22 and leak resistor 23 connected to the output circuit of the amplifier 14. The output circuit of the tube 20 includes the primary winding 24 of a transformer 25, the secondary winding 26 of which is coupled to the diode peak rectifier 21 provided with a load circuit comprising a parallel-connected resistor 27 and condenser 28 having a large time constant. This time constant should be considerably greater than the period of the line-synchronizing pulses. For conventional systems utilizing, for example, 30 frames (60 fields) of 441 lines per second, the resistor 27 may be of the order of 500,000 ohms and the condenser 28 of the order of 500 micro-

microfarads providing a time constant of .00025 second.

For the purpose of deriving the synchronizing pulses separate from the other modulation pulses, impedance means, specifically, a resistor 29 may be included in series with the condenser 28 and the diode 21 as shown. The resistor 29 is of such value as to have a relatively low impedance compared to that of the condenser 28 at the synchronizing frequencies. The input circuits of the line-frequency and field-frequency generators 18 and 19 are connected across the resistor 29 by way of a suitable lead 30. Conventional circuits may be included in the generators 18 and 19 for separating the line-synchronizing and field-synchronizing pulses from each other. The negative terminal of resistor 29 is connected, by way of a suitable filter including series resistors 31 and shunt condensers 32 and conductors 33, to the control electrodes of one or more of the vacuum tubes included in the amplifier 12, oscillator-modulator 13, and amplifier 14, as shown.

The operation of the system in accordance with the present invention may best be explained with reference to the curves of Fig. 2, in which curve A illustrates the load characteristics of the peak rectifier 21, the abscissae representing applied alternating voltage and the ordinates representing the load current. The applied voltage, derived from a signal translated by the receiver and having signal components including the peaks of the synchronizing modulation components at a level corresponding to the unmodulated peaks of the carrier wave, is illustrated by curve C, which shows the wave form of the envelope of the negatively modulated-carrier signal as developed in the output circuit of the intermediate-frequency amplifier 14 and applied by way of the tube 20 and transformer 25 to the diode 21. For the purpose of simplicity, only a few line-frequency cycles are shown. The means for applying this signal to the diode 21 is also effective to maintain the peaks of the synchronizing modulation components at the above-mentioned level. The light-modulation components and synchronizing-modulation components are indicated at L and S, respectively, the latter, it will be noted, extending beyond the amplitude range of the former. Signal levels corresponding to white and black are indicated in the figure at W and B, respectively.

It will be seen that the peak rectifier 21 passes current only during the occurrence of synchronizing pulses, which represent the peak values of the modulated-carrier wave on one side of its axis, this being determined by the large time constant circuit provided by the resistor 27 and condenser 28. There is thus built up across the load circuit 27, 28 a unidirectional voltage, illustrated at e in Fig. 2, which is the peak-rectified applied signal. That is, the average value of this voltage is proportional to the maximum amplitude of the carrier wave and independent of light-modulation components. The filter comprising the resistors 31 and condensers 32 serves to remove residual fluctuations from the rectified voltage and the resultant steady unidirectional bias voltage is impressed negatively on the control grids of one or more of the tubes in the stages 12, 13 and 14 to control the amplification of these stages inversely in accordance with the maximum value of carrier-wave amplitude and independently of light-modulation components. Thus, the output signal intensity of the main signal-translating channel is maintained within a relatively narrow

range for a wide range of received signal intensities.

Since the diode 21 passes current only during the occurrence of the synchronizing pulses, representing the charging current of condenser 28, this current flows through the resistor 29, which is in series with the diode, and there are thus developed across this resistor synchronizing pulses free from the light-modulation components of the signal, as illustrated by curve *t* of Fig. 2. These pulses are applied to the generators 18 and 19, in which conventional separating apparatus serves to separate the line-synchronizing and field-synchronizing pulses from each other and these pulses are utilized to maintain the generators 18 and 19 in synchronism with the corresponding apparatus at the transmitter, in the usual manner.

The single rectifying circuit described above thus serves to derive from the signal both a unidirectional bias voltage proportional to the intensity of the modulated-signal carrier and independent of its light-modulation components and the synchronizing-modulation components separate from the other modulation components.

Fig. 3 shows a diode rectifier arrangement which may be substituted for that shown in Fig. 1. Here the arrangement is the same as in Fig. 1 except that resistor 29 is connected between the diode cathode and its load circuit rather than in its load circuit. The operation of this arrangement is substantially the same as that of Fig. 1.

It is to be noted that the control system of the present invention may be energized with the detected signal as well as the modulated-carrier signal. In that case, the input circuit of rectifier 21 may be directly connected, that is, connected by a direct current connection, to the output circuit of the detector 15 instead of the amplifier 14 and the detected modulation-signal envelope, that is, the envelope of half the wave C shown in Fig. 2, is impressed on the diode rectifier 21. The operation is otherwise the same as that described above. In other words, an essential feature of the arrangement of the invention is that the signal rectifying means be energized by a signal translated by the receiver and having components representing the peaks of the synchronizing-modulation components at a level corresponding to the unmodulated peaks of the received signal-carrier wave.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A television receiver adapted to reproduce a signal-carrier wave having combined light-modulation components and synchronizing-modulation components having amplitude values outside the amplitude range of a light-modulation components comprising, a rectifying device, means for deriving from a signal translated by said receiver a signal having components representing the peaks of said synchronizing-modulation components at a level corresponding to the unmodulated peaks of said carrier wave, means for applying said derived signal to said device including means for maintaining said peaks at said level to derive said synchronizing com-

nents separate from said other modulation components and a control effect proportional to the intensity of said carrier wave and independent of light-modulation components, means for utilizing said control effect for controlling an operating characteristic of the receiver, and means for utilizing said separated synchronizing components for synchronizing the operation of the receiver.

10 2. A television receiver adapted to reproduce a television signal-carrier wave having combined light-modulation components and synchronizing-modulation components having amplitude values outside the amplitude range of the light-modulation components comprising, a main signal-translating channel, a separate control signal-translating channel, means for applying a signal translated by said receiver and having components representing the peaks of said synchronizing-modulation components at a level corresponding to the unmodulated peaks of said carrier wave to both of said channels, a rectifying device included in said control channel, means for applying said signal applied to said control channel to said device including means for maintaining said peaks at said level to derive said synchronizing components separate from said other modulation components and a control effect proportional to the peak intensity of said carrier wave and independent of light-modulation components, means for utilizing said control effect for controlling an operating characteristic of said main channel, and means for utilizing said separated synchronizing components for synchronizing the operation of the receiver.

3. A television receiver adapted to reproduce a television signal-carrier wave having combined light-modulation components and synchronizing-modulation components having amplitude values outside the amplitude range of the light components, comprising, a main signal-translating channel, a separate control signal-translating channel, means for applying a signal translated by said receiver and having components representing the peaks of said synchronizing-modulation components at a level corresponding to the unmodulated peaks of said carrier wave to both of said channels, a rectifying device included in said control channel, means for applying said signal applied to said control channel to said device including means for maintaining said peaks at said level to derive a control-bias voltage proportional to said peak value of said carrier wave and to develop from said signal said synchronizing components separate from the other modulation components, means for utilizing said control-bias voltage for controlling an operating characteristic of said main channel, and means for utilizing said separated synchronizing components for synchronizing the operation of the receiver.

4. A television receiver adapted for the reception of a television signal-carrier wave modulated negatively by light components and modulated by synchronizing components having amplitude values outside the amplitude range of the light components, a rectifying device, means for deriving from a signal translated by said receiver a signal having components representing the peaks of said synchronizing-modulation components at a level corresponding to the unmodulated peaks of said carrier wave, means for applying said derived signal to said device including means for maintaining said peaks at said

level to derive a control-bias voltage proportional to the peak value of said carrier on one side of its axis and to derive said synchronizing components separate from said other modulation components, means for utilizing said control-bias voltage for controlling an operating characteristic of the receiver, and means for utilizing said separated synchronizing components for synchronizing the operation of the receiver.

5. A television receiver adapted for the reception of a television signal-carrier wave modulated negatively by light components and modulated by synchronizing components having amplitude values outside the amplitude range of the light components, a main signal-translating channel, a separate control signal-translating channel, means for applying a signal translated by said receiver and having components representing the peaks of said synchronizing-modulation components at a level corresponding to the unmodulated peaks of said carrier wave to both said channels, a rectifying device included in said control channel, means for applying said signal applied to said control channel to said device including means for maintaining said peaks at said level to derive a control-bias voltage proportional to the peak value of said carrier on one side of its axis and to derive said synchronizing components separate from said other modulation components, means for utilizing said control-bias voltage for controlling an operating characteristic of said main channel, and means for utilizing said separated synchronizing components for synchronizing the operation of the receiver.

6. A television receiver adapted to reproduce a signal-carrier wave having combined light-modulation components and synchronizing-modulation components having amplitude values outside the amplitude range of the light components, said wave having a wide range of signal-input intensities, comprising, a rectifying device means for deriving from a signal translated by said receiver a signal having components representing the peaks of said synchronizing-modulation components at a level corresponding to the unmodulated peaks of said carrier wave, means for applying said derived signal to said device including means for maintaining said peaks at said level to derive a control-bias voltage proportional to the intensity of said carrier wave and independent of light-modulation components and to derive said synchronizing components separate from the other modulation components, means for utilizing said control-bias voltage for maintaining the intensity of the signal output of said receiver within a relatively narrow range for a wide range of received signal input intensities, and means for utilizing said synchronizing components to synchronize the operation of the receiver.

7. A television receiver adapted to reproduce a signal-carrier wave having combined light-modulation components and synchronizing-modulation components having amplitude values outside the amplitude range of the light components, said wave having a wide range of signal-input intensities comprising a main signal-translating channel, a separate control signal-translating channel, a rectifying device, means included in said control channel for deriving from a signal translated by said receiver a signal having components representing the peaks of said synchronizing-modulation components at a level corresponding to the unmodulated peaks of said

carrier wave, means for applying said derived signal to said device including means for maintaining said peaks at said level to derive a control bias voltage proportional to the intensity of said carrier independent of light modulations and to derive said synchronizing components separate from the other modulation components, means for utilizing said control-bias voltage for maintaining the intensity of the signal output

5 of said main channel within a relatively narrow range for a wide range of received signal input intensities, and means for utilizing said synchronizing components to synchronize the operation of the receiver.

10 15 8. A television receiver adapted to reproduce a signal-carrier wave having combined light-modulation and synchronizing-modulation components having amplitude values outside the amplitude range of the light-modulation components, comprising, a diode rectifier, means for deriving from a signal translated by said receiver a signal having components representing the peaks of said synchronizing-modulation components at a level corresponding to the unmodulated peaks of said carrier wave, means for applying said derived signal to said device including

20 25 30 means for maintaining said peaks at said level to derive a control-bias voltage proportional to the intensity of the carrier wave and independent of its light-modulation components, impedance means in circuit with said rectifier for deriving from said signal synchronizing components separate from the other modulation components, means for utilizing said control-bias voltage for controlling an operating characteristic of the receiver, and means for utilizing said separated synchronizing components for synchronizing the operation of the receiver.

35 40 9. A television receiver adapted to reproduce a signal-carrier wave having combined light-modulation and synchronizing-modulation components having amplitude values outside the amplitude range of the light-modulation components, comprising a diode rectifier having a load circuit including a resistor and condenser connected in parallel and providing a time constant circuit, means for deriving from a signal translated by said receiver a signal having components representing the peaks of said synchronizing-modulation components at a level corresponding to the unmodulated peaks of said carrier wave, means for applying said derived signal to said device including means for maintaining said peaks at said level to derive a control-bias voltage proportional to the intensity of the carrier wave and independent of its light-modulation components, a resistor connected in series with said diode and said condenser for deriving from said signal synchronizing components separate from the other modulation components, means for utilizing said control-bias voltage for controlling an operating characteristic of said receiver, and means for utilizing said separated synchronizing components for synchronizing the operation of the receiver.

45 50 55 60 65 70 10. A television receiver adapted to reproduce a signal-carrier wave having combined light-modulation and synchronizing-modulation components having amplitude values outside the amplitude range of the light-modulation components, comprising a main signal-translating channel, a separate control signal-translating channel, means for applying a signal translated by said receiver and having components representing the peaks of said synchronizing-modu-

lation components at a level corresponding to the unmodulated peaks of said carrier wave to said channels, a diode rectifier included in said control channel, means for applying said signal applied to said control channel to said device including means for maintaining said peaks at said level to derive a control-bias voltage proportional to the peak value of said signal-carrier wave on one side of its axis, impedance means in

5 circuit with said rectifier for deriving from said signal synchronizing components separate from the other modulation components, means for utilizing said control-bias voltage for controlling an operating characteristic of the receiver, and means for utilizing said separated synchronizing components for synchronizing the operation of the receiver.

HAROLD M. LEWIS.
